FINGER RING

Valmore Guertin and Emile H. Guertin, both of
372 Main St., Hyannis, Mass.

Filed Nov. 7, 1960, Ser. No. 62,746

Term of patent 14 years
(Cl. D45—10)

F I G. 1

F I G. 2

F I G. 3

F I G. 4

F I G. 5

Figure 1 is a perspective view of a finger ring showing our new design;

Figure 2 is a front elevation of the same;

Figure 3 is a bottom plan view of the same;

Figure 4 is an elevational view of the ring as seen from the left in Figure 2; and

Figure 5 is an elevational view of the ring as seen from the right in Figure 2.

We claim:

The ornamental design for a finger ring, as shown.
